UNITED STATES PATENT OFFICE

155,023

DESIGN FOR A CHAIR

Theodore T. Michals, Chicago, Ill.

Application May 17, 1948, Serial No. 146,412

Term of patent 7 years

(Cl. D15—1)

To all whom it may concern:

Be it known that I, Theodore T. Michals, a citizen of the United States, residing at Chicago, in the county of Cook and State of Illinois, have invented a new, original and ornamental Design for a Chair, of which the following is a specification, reference being had to the accompanying drawing, forming part thereof.

I claim:

The ornamental design for a chair, as shown.

THEODORE T. MICHALS.
